WARNING CLOCKWORK INSTRUMENT

Jean d'Angely, Paris, and René Linard, Montbeliard, France, assignors to Etablissements Japy Frères, Société Anonyme, Paris, France, a company of France

Application September 15, 1950, Serial No. 185,032
In France October 13, 1949

6 Claims. (Cl. 58—21.14)

1

Clockwork instruments are known, such as alarm clocks, which have the object of indicating, especially by audible means, the ends of a period of time previously fixed on the instrument by the movement of a hand. In general, they are used to produce audible signals after a period of operation lying between a minimum of fifteen minutes and a maximum of eleven hours, with an error of operation varying approximately between three and five minutes owing to the mechanism itself and depending upon the judgment of the user when moving the alarm hand on the corresponding dial.

For these reasons, clockwork instruments comprising a normal alarm system cannot be employed as warning devices having a short-term operation, for example of the order of one minute. In order to remedy this deficiency, clockwork devices known as minute movements have been provided, such for example as time meters operated electrically or by other means, which are arranged to set in operation a ringing mechanism after a period of operation of between 0 and 60 or 120 minutes with sufficient precision. However, such instruments are limited to their metering operation and do not indicate the time. It is also known, for example as disclosed in French patent specification No. 942,575 of March 1, 1947, to provide in association with an ordinary alarm clock an indicating system with means for operating a ringing system after a short time.

The instrument described in the said specification is limited in its period of operation to 2 to 58 minutes by its very conception. Moreover, the arrangement temporarily takes energy, in the form of friction from the clockwork movement to which it is applied, whereby anomalies may arise in operation.

The present invention overcomes these disadvantages.

In accordance with the invention, there is provided in association with a clockwork mechanism comprising an alarm bell a metering and warning mechanism controllable from the outside, which is subjected to the action of a return spring and normally disengaged from the clockwork mechanism but arranged to be connected thereto through friction means. The said mechanism is kinematically connected on the one hand to a metering device and on the other hand to a rocking member terminated by a forked portion, the two noses of which may serve alternately to stop the striking anchor.

Thus, by manual actuation of this mechanism it is engaged and moved against friction in the

opposite direction to the clockwork movement. In this operation, the metering member is brought in front of a time indicating means, while one of the noses of the rocking member is substituted for the other by the locking of the striking anchor.

When the action on the mechanism is discontinued, the clockwork movement drives the said mechanism at its own speed in the opposite direction through the friction, whereby the metering device is progressively returned to its initial position and the change over of the stop noses of the striking anchor is brought about at slow speed at the end of the movement. During this changeover, the bell is rung.

It is obvious that it is possible by the choice of the gear ratios employed in the metering and warning mechanism to choose arbitrary times limited simply by the motion of the clockwork movement with which the metering and warning device is associated. In practice, these times will be limited to a maximum duration of 120 minutes, which is sufficient for most purposes. Moreover, the said metering and warning mechanism does not take energy from the clockwork movement since its return spring can not only compensate for the actual friction of the said metering device, but can also supply additional energy to this clockwork movement.

In an advantageous embodiment of the invention, the nose of the rocking member, which is normally engaged with the striking anchor, may be subjected to an elastic force perpendicular to the plane of the fork and may cooperate with the usual operating cam of the ringing mechanism of alarm clocks instead of the usual spring acting axially on the said cam. The cam is thus able in the usual manner to control also the ringing mechanism.

The description hereinafter given with reference to the accompanying drawings, which are given by way of non-limitative example, will enable the manner in which the invention can be carried into effect to be readily understood, the details appearing both from the text and the drawings naturally forming part of the said invention.

Figure 1 is a view in perspective of the metering and warning device associated with an alarm movement.

Figure 2 shows a variant of the connection of the aforesaid warning device to the time movement to which it is applied, and

Figures 3, 4 and 5 show a variant of the device for operating the ringing mechanism.

Figures 1, 2 and 3 show a number of parts nor-

mainly employed in alarm clocks, namely the pin of the minute hand 1, the cannon pinion 2 rigidly mounted on the pin, the minute wheel 3 and its pinion 4, the cannon wheel 5, the cannon 6 supporting the hour hand 7, the cam wheel 8 and the operating cam 9, the pin 10 for setting the alarm, the button 11 thereof, the operating dog 12 thereof, and the alarm hand 13 thereof, the minute hand 14, the alarm anchor pin 15, the anchor 16, the striker rod 17 with the striker 18 and the stop rod 19.

Apart from these known parts, Figure 1 shows a toothed wheel 20 arranged to turn on the minute pin 1 with a friction determined by a spring 21. Situated in the same plane as the wheel 20 and arranged to mesh therewith is a toothed sector 22 riveted to a supporting cannon 23 and connected in turn to another toothed sector 24, the whole assembly turning about a pin 25 parallel to the axis of the minute hand 1.

In the same plane as the sector 22 a pinion 26 for operating the metering and warning device meshes with the said sector. This pinion is mounted on a pin 27 which extends out of the casing of the movement and is provided with a control button 28. The pin 27 carries a dog 29 to which is secured one end of a spring 30, the other end of which is connected to a fixed point of the movement at 31. The spring is wound so as to tend to produce rotation of the pin 27 and of the pinion 26 in the direction of the arrow 32.

The engagement between the pinion 26 and the sector 22 is limited by the action of a stud 22a which abuts either against the pinion 26 as shown in the drawings or against the wheel 20 if the sector 22 is turned in the direction of the arrow 22b. In the plane of the sector 24, a wheel 33 riveted to a cannon 34 turns freely on the cannon 6. The cannon 34 carries the hand 35 for setting the metering device to the required time. By way of example, the starting point of this hand is at 35a and the limit of its movement is at 35b. One of the features of the invention is that it allows of determining the total angular displacement of this hand, which may be less than, equal to or greater than 360°, by providing suitable gear ratios between the sectors 22 and 24 and the wheels 20 and 33 respectively.

The hand 35 is held in its initial position by a spring 36 acting on a flat 34a machined on the cannon 34. It is also possible to provide another spring producing a similar action to the spring 36, but diametrically opposite thereto on the cannon 34 in order to balance the pressures exerted on the cannon 34 with a view to preventing increase in the friction thereof during the rotation. In an embodiment not shown in the drawings, the hand 35 may also be returned to zero by the action of a spiral spring, the effect of which is limited by the provision of a stop on the hand 35 (this device is advantageous owing to the fact that it tends to cancel out the irregularities produced by the sets of gears).

The sector 22 carries rollers 37 to replace, for the sake of convenience a cam also provided. These rollers 37 cooperate with a rocking member, which in the present case is an operating lever 38 pivoting at 38a. The upper part of this lever is divided into two arms 38b and 38c. The arm 38c is elastically tensioned against the operating cam 9 and follows the movements thereof in the direction of the arrow 39 or vice versa, which has the effect of releasing or locking the stop rod 19 by its bent-over extremity 19a. This function is that of the normal release of the

alarm. The lever 38 is subjected to the action of the return spring 41 acting in the direction of the arrow 42, which forces it against the rollers 37.

5 The arrangement operates in the following manner: The parts shown in Figure 1 are in the position in which the metering and warning device is not in operation, that is to say with the hand 35 at zero and with the sectors 22 and 24 not in engagement with the wheels 20 and 33 respectively. In this position, the ringing of the alarm takes place in the usual way by the action of the cam 9, which disengages or locks the stop rod 19 for the relative elastic movements of the arm 38c.

10 In order to use the metering device independently of the alarm, the button 28 is turned in the direction of the arrow 43, which produces the rotation of the sectors 22 and 24 in the direction of the arrow 22b. Each of these sectors then meshes with the wheels 20 to 33, which brings about the following simultaneous actions:

15 1. Coupling of the device with the time movement, the wheel 20 being engaged with the sector 22, this wheel, mounted with friction on the pin 1, has been able to turn under the action of the sector without causing any disturbance of this pin 1.

20 2. Increase of the return force of the spring 30.

25 3. Displacement of the hand 35 of the metering device to the desired graduation (indicating the number of minutes after which the warning device is to function), by the action of the sector 24 which causes the wheel 33 carrying the cannon 34 and the hand 35 to turn.

30 4. The operating lever 38 has turned through a certain angle under the thrust of the rollers 37 acting on the arm 38d. It follows that the upper arms 38b and 38c have turned in the direction of the arrow 49 to the point where the arm 38c has released the stop rod 19a while at the same time the arm 38b has again locked the rod 19a.

35 The operation of the metering device commences from the instant when the button 28a is released. At this instant, the clockwork movement, through the wheel 20 returns the sectors in the direction opposite that of the arrow 22b. This rotation is assisted by the action of the spring 30, which expands and supplies energy to the movement. The meter hand 35 returns to

40 its initial position (zero) and indicates constantly the time which has to elapse. When it reaches zero, the lever 38 has moved in the direction of the arrow 42 under the action of the spring 41 and due to the retraction of the rollers 37.

45 5. Simultaneously the arm 38b has released the ringing stop rod 19a, whereby the bell is started. Obviously, the barrel of the ringing mechanism (not shown in Figure 1) must have been rewound after the setting of the metering device to the required hour.

60 After the operation of the ringing mechanism defined above, the sector 22 and the wheel 20 remain in engagement for a few instants in order that the arms 38b and 38c may be slowly returned to their initial position, which gives the ringing mechanism a normal period of operation. It will be understood that the space between the ends 38b and 38c is greater than the width of the part 19a of the stop rod 19. Ultimately, the engagement between the wheel 20 and the sector 22 ceases, the time movement is released again by disengagement of the sector 22 and the parts return to the position shown in Figure 1.

65 70 75 It is possible without departing from the prin-

5
ciple of the invention to envisage a number of modified embodiments, merely by way of example.

It is apparent notably that the sector 22 can come into contact with a wheel 20 which may be fixed to a movable part of the clockwork mechanism other than that carrying the minute hands, that intermediate wheel systems may be provided between these two parts to obtain different gear ratios or to stagger the pins for convenience of construction.

The meshing of the sector 22 with the teeth of the wheel 20, that is to say the engagement of the said sector, is facilitated by modifying the length or form of the first tooth 22a of this sector, for example. The control of the metering device by the button 28, instead of acting through the pinion 26 on the sector 22, may be made to turn the sector 24 or even a further wheel provided on the mounting of these sectors. In addition, the button 28 may be situated in front of the instrument and even on the side, an angular transmission of movement being employed. The sector 24 may also be replaced by a toothed wheel also engaging with the wheel 33 if it is considered that a return of the hand 35 beyond the zero position is desirable, that is to say a return equal to the time elapsing between the operation of the ringing mechanism and disengagement of the sector 22 and the wheel 20.

Figure 2 shows a variant of the connection of the warning device to the time movement. This variant is characterised by the use of gears, in permanent engagement contrary to the system of sectors in which the engagement is temporary. This permanent connection of the gears is associated with an engaging system which may be of any desired form and which is engaged by the starting of the metering device and disengaged at the end of the operation thereof.

The cannon pinion 2 engages with a wheel 44 which is riveted to the boss 45 having a groove 45a and turning freely on a pin 46. A plate 47 is connected to the said pin 46 and limits laterally the movement of the boss 45. The said plate is provided with engaging means, for example a stud 48 serving as a fixed base for a spring 49. The said spring rests in the groove 45a when its extremity is not lifted by a pin 50 secured to the movement. The spring 49 bearing in the groove 45a, in which good conditions of adhesion are provided (trapezoidal groove, materials of high coefficient of friction, roughening, etc., for example), provides the engagement between the boss 45 and the shaft 46.

A wheel 51 is connected to the shaft 46 and drives a wheel 52 mounted on a cannon 53 which receives the hand 54 for setting the meter to the required time. The said wheel 51 is controlled by a pinion 55 mounted on a control rod 56 which extends out of the casing. A button 57 is secured to the said rod. As in Figure 1, this rod 56 is subjected to the action of a spring 59 which acts on a dog 58. The relative movements of the gears 51, 52 and 55 are limited by a stop 51a which in turn forms part of the wheel 51 or which may be arranged in any other manner.

The shaft 46 supports a cam 60 rigidly connected thereto, and on rotation produces movements of the operating lever 61 through a roller 62. In its upper part, the operating lever 61 is identical to that described with reference to Figure 1.

In this variant, the operation is as follows:

If the button 57 is turned in the direction of

the arrow 63, the following actions occur simultaneously:

1. Displacement of the hand 54 to the required position by the rotation of the wheels 55—51—52.
2. Tensioning of the spring 59.
3. Rotation of the shaft 46, which in turn has two functions:

(a) It drives the plate 47 in the direction of the arrow 64. At this instant, the spring 49 leaves the position in which it bears against the pin 50 and becomes engaged in the groove 45a in which it exerts, by pressure, a friction calculated to permit sliding when the plate 47 turns without having to drive the wheel 44 (during the setting of the meter to the required time), and driving of the plate 47 and of the shaft 46 by the wheels 44 and 2 when the metering device operates after the release of the button 57.

(b) It drives the cam 60, which actuates the operating lever 61, whereby the operation explained with reference to Figure 1 is brought about.

These various operations having taken place at the instant when the meter has been set to the required time by the user, the apparatus automatically carries out the following functions under the regulating action of the time movement. The cannon pinion 2 slowly turns the wheel 44, which drives the whole assembly mounted on the shaft 46 (in the opposite direction to the arrow 64), owing to the spring 49 which is in the engaged position (this rotation is assisted by the energy accumulated in the spring 59 during the setting to the required time). Consequently, the needle 54 returns to zero and the other parts progressively take up the position shown in Figure 2. The cam 60, in passing, sets in operation by means of its slope 60a, the ringing mechanism of the metering device and by its slope 60b, a few instants afterwards, it returns the operating lever to the alarm position, while simultaneously disengaging the boss 45 by lifting the spring 49 on the pin 50.

Figures 3, 4 and 5 show a variant of the operating arrangement. This variant may be associated with any of the means for connecting the metering system to the time movement hereinbefore described. More especially Figure 3 shows the type of connection in which toothed sectors are employed as shown in Figure 1. It will be noted that the operating lever 65 does not bear directly against the cam 9. A disengaging spring 66 connected to the movement transmits to the arm 65a, by means of its extremity 66a, the relative displacements controlled by the cam 9, in the direction of the arrow 67 or in the opposite direction thereto, so that the alarm ringing mechanism is released (Figure 4) or locked (Figure 3) by the action of the nose 65b. The lever 65 subjected to the action of the rollers at its part 65d at the instant when the meter is set to the required hour, turns in the direction of the arrow 40 and takes up the position shown in Figure 5, in which the nose 65c locks the part 19b of the stop rod. Due to the operation of the metering device, the lever 65 slowly returns to the rear in the direction of the arrow 40. The arrangement is such that when the hand 35 for setting the metering device to the required time returns to zero, the nose 65c releases the part 19b of the stop rod 19, whereby the ringing mechanism is enabled to operate. The distance between the noses 65b and 65c is such that the nose 65b can only lock the stop rod in its bent portion when the ringing mechanism has functioned for the

whole of the necessary time. Subsequently, the lever returns to its initial position and again takes up the position shown in Figure 3 or 4, in which the usual alarm is in the position of use or is ready for operation.

The indication of the metering time as described in the foregoing, which is given by a needle moving past a minute scale, is not limited to these means. Other forms of embodiment are also possible, such as a dial turning behind the usual dial, which has an opening through which the graduation can be seen. Similarly the meter needle may be situated outside the minute pin or usual hands and in particular on the axis of the sectors 25, it may be disposed with its corresponding graduation on the front and rear faces of the instrument.

For certain purposes requiring a more precise appreciation of short times than of long times, the sector 24 and the wheel 33, or the equivalents thereof, may be given teeth of variable ratio in order to obtain in the neighbourhood of zero, as a function of time, larger angular displacements of the hand 35.

The invention hereinbefore described gives visual and audible indications determining the end of a fixed time. It is obvious that each of the operative parts of the system, that is the means for setting the metering device to the required time, the means for controlling the operating lever, the lever itself, the ringing barrel, the hand of the metering device and its rotatable support, for example may be employed to control contacts intended to open or close electric circuits for numerous purposes.

It will be obvious that modifications may be made to the clockwork instrument hereinbefore described, notably by substitution of equivalent technical means, without departing from the scope of the present invention.

What we claim is:

1. In an alarm clock including a clockwork associated with an alarm movement having control means accessible from the outside and an alarm device including a stop rod, and with a graduated time metering device provided with further control means accessible from the outside, the combination of a rocking member provided with two opposite noses adapted to come selectively into abutment with said stop rod; means for coupling said metering device with said clockwork; connecting means between said metering device and said rocking member for rocking the latter into abutting position of either of said noses; and a mechanical link between said connecting means and said coupling means.

2. In an alarm clock including a clockwork associated with an alarm movement having control means accessible from the outside and an alarm device including a stop rod, and with a graduated time metering device provided with further control means accessible from the outside, the combination of a rocking member; a nose on said rocking member, adapted to come into abutment with said stop rod; resilient means for urging said nose out of abutment from said stop rod, parallelly to the rocking axis of said rocking member; a further nose on said rocking member, adapted to come into abutment with said stop rod opposite to the former mentioned nose; means for coupling said metering device with said clockwork; spring means acting on said rocking member for urging said former mentioned nose into abutting position and said further nose out of abutment; and cam means associated with

5 said coupling means for rocking said rocking member against the action of said spring means.

3. A combination according to claim 2, further comprising further spring means for urging said metering device into uncoupled position.

4. In an alarm clock including a clockwork associated with an alarm movement having control means accessible from the outside and an alarm device including a stop rod, and with a graduated time metering device provided with further control means accessible from the outside, the combination of a rocking member; a nose on said rocking member, adapted to come into abutment with said stop rod; resilient means for urging said nose out of abutment from said stop rod, parallelly to the rocking axis of said rocking member; a further nose on said rocking member adapted to come into abutment with said stop rod opposite to the former mentioned nose; means for coupling said metering device with said clockwork; a cam, the outline of which includes substantially an arc of a circle and a recess adjacent an end of said arc of a circle, said cam being associated with said coupling means 10 and being in contact relationship with a part of said rocking member, whereby said recess corresponds to abutting position of said former mentioned nose and to disengagement position of said coupling means, and said arc of a circle corresponds to abutment of said further nose and to engagement position of said coupling means; and spring means for urging said part of said rocking member into contact with said cam.

5. In an alarm clock including a clockwork 15 associated with an alarm movement having control means accessible from the outside and an alarm device including a stop rod, and with a graduated time metering device provided with further control means accessible from the outside, the combination of a rocking member; a nose on said rocking member, adapted to come into abutment with said stop rod; resilient means for urging said nose out of abutment from said stop rod, parallelly to the rocking axis of said rocking member; a further nose on said rocking member, adapted to come into abutment with said stop rod opposite to the former mentioned nose; a gearing frictionally connected to said clockwork; means for coupling said gearing with said metering device; spring means acting on said rocking member for urging said former mentioned nose into abutting position and said further nose out of abutment; cam means associated with said coupling means for rocking said rocking member against the action of said spring means; and further spring means for urging said metering device into uncoupled position.

6. In an alarm clock including a clockwork 20 associated with an alarm movement having control means accessible from the outside and an alarm device including a stop rod, and with a graduated time metering device provided with further control means accessible from the outside, the combination of a rocking member; a nose on said rocking member, adapted to come into abutment with said stop rod; resilient means for urging said nose out of abutment from said stop rod, parallelly to the rocking axis of said rocking member; a further nose on said rocking member, adapted to come into abutment with said stop rod opposite to the former mentioned nose; gearing on said clockwork; means for frictionally coupling said gearing with said metering device; spring means acting on said rocking member for urging said former mentioned nose into

abutting position and said further nose out of abutment; cam means associated with said coupling means for rocking said rocking member against the action of said spring means; and further spring means for urging said metering device into uncoupled position.
